LUBRICATOR

Carl L. Daun, Milwaukee, Wis., assignor, by direct and mesne assignments, of one-half to William F. Daun, Saginaw, Mich., and one-half to L. Roy Smith and Minta A. Smith, Wauwatosa, Wis.

Application October 30, 1933, Serial No. 695,762

3 Claims. (Cl. 184—103)

This invention relates to an improvement in lubricators adapted for supplying the proper amount of lubricant to various types of bearings and in its present embodiment the invention is particularly adapted for average industrial service.

Among the objects of the invention are to provide a lubricator of this character, simple, durable and yet compact and of lightweight construction, one which is efficient and reliable in operation and yet requires no attention or adjustment. The lubricator may be employed with equal advantage as a constant level lubricator for use with oil wells or anti-friction bearings and as a wick feed lubricator for the sleeve type of bearing. It may be employed either selectively for these purposes or they may be utilized to function simultaneously in feeding the correct amount of lubricant to several different types of such bearings.

Another object of the invention is to provide a lubricator having these advantages and capacities and yet lends itself to equivalent and economical manufacture.

Other objects and advantages reside in certain novel features of the construction, arrangement and combination of parts which will be herein-after more fully described and particularly pointed out in the appended claims, reference being had to the accompanying drawings, forming a part of this specification, and in which:

Figure 1 is a view partly in side elevation and partly in transverse vertical section showing a lubricator embodying the present invention;

Figure 2 is a fragmentary sectional view taken on line 2—2 of Figure 3;

Figure 3 is a view in horizontal section taken on line 3—3 of Figure 1 with parts broken away to more clearly show the construction;

Figure 4 is a detail perspective view of the stopper or sealing plug provided for the main container or reservoir;

Figure 5 is a view similar to Figure 1 but showing another embodiment of the invention;

Figure 6 is a view in vertical section taken on line 6—6 of Figure 5; and

Figure 7 is a view in horizontal section taken on lines 7—7 of Figure 5 with parts broken away to more clearly show the construction.

Referring to the drawings, and more particularly to Figures 1 to 4, inclusive, it will be seen that the lubricator comprises a cup or base fitting designated generally at 1, the cup 1 having a body portion 2 formed interiorly with an oil chamber 3, there being an opening 4 above

the oil chamber 3 to receive the collar 5 that surrounds the lower end or neck 6 of a main container or reservoir 7.

The container or reservoir 7 may be in the form of an inverted jar and it is united to its collar 5 by a layer of suitable plastic designated at 8 and which may be porcelain or the like.

The collar 5 is flanged as at 9 so as to engage the top of the base fitting and support the container 7 in position and this flange 9 has a flanged 10 lateral extension 10 to provide a top or cover for the lateral extension 11 of the base fitting.

Vertical openings 12 and 13 are provided in the lateral extension of the base fitting, the opening 12 forming a continuation of the oil 15 chamber and the opening 13 a standpipe as well as a wick feed outlet. A portion of the collar 5 extends across and blocks the communication of the opening 12 with the opening 4. The lower end of the neck of the reservoir 7 determines 20 and controls the oil level in the oil chamber and in the construction illustrated the collar 5 also terminates at the oil level.

As illustrated, the opening 13 extends down through the bottom of the fitting and has its 25 lower end internally threaded as at 14 to adapt it for connection with a pipe leading to an air screen intake or to a bearing. A wall 15 separates the openings 12 and 13 of the extension for the greater part of their length but terminates short of the upper ends of the openings so as to afford a communicating passage 16 there-between. The base fitting is also provided with one or more peripheral outlets 17 and a bottom outlet 18, either one or both of which may be 35 employed. When not employed they may be conveniently capped or plugged.

The outlet 17 may be connected by a suitable pipe to an oil well type of bearing whereas the outlet 18 might be connected by means of a U-40 shaped pipe with an anti-friction type of bearing. Where the outlet 14 is connected to a sleeve type of bearing, a wick 19 is provided and has a portion immersed in the oil in the oil chamber and is then extended up through the opening 12, 45 across the upper end of the wall 15 and down through the standpipe 13. To facilitate assembly of a container 7 with the base fitting and avoid spilling of oil, a stopper 20 may be provided and consists of a cone of resilient sheet 50 metal which is split at spaced points as indicated at 21 and which has a stop or handle 22 connected therewith. When a container with oil therein is inverted and disassembled from the base fitting the cone drops down into the neck 55

and prevents loss of oil or flow thereof through the neck of the container. In the assembly, however, the lower end of the stop or handle 22 bears against the bottom of the base fitting to lift the cone away from the neck of the container and allow flow of oil therethrough. In the drawings the size of the splits 21 is exaggerated for the sake of clearness of illustration. However, when the stopper 20 is in position to close the opening through the neck the engagement of the stopper with the neck results in a contraction of the resilient cone and an effective closing of the splits. Assembly of the stopper with the reservoir is also taken care of by the flexure of the resilient sections of the stopper with respect to each other.

The form of the invention shown in Figures 5 to 7, inclusive, is identical with that just described and the above description applies thereto with the exception of the manner in which the extension of the base fitting is constructed. The extension which is designated at 25 is formed with three openings instead of two, the openings being designated at 26, 27, and 28 and being separated from each other for the major portion of their length by means of walls 29 and 30. These walls 29 and 30 terminate short of the upper ends of the openings to provide connecting passages 29' and 30' therebetween. The outside openings 26 and 28 provide the standpipes and extend down through the bottom of the fitting and also have their lower portions internally threaded as indicated at 31. The intermediate opening 27 forms a continuation of the oil chamber as before.

With this construction, the lubricator is adapted to provide a wick feed of oil to two sleeve type bearings, wicks 33 and 34 being extended from the oil chamber up over the walls 29 and 30 and down through the standpipes 26 and 28. Both embodiments of the invention may be advantageously employed to lubricate a plurality of bearings, even though the bearings be of different types, the outlet 17 may have a straight horizontal type connection with an oil well type of bearing and affords a constant uniform feed of oil thereto. Simultaneously with this action the outlets 18 may be employed to supply lubricant to anti-friction types of bearings and the standpipes 13, 26 and 28 may be employed to supply a wick feed of lubricant to sleeve type bearings. The construction is highly compact and very simple and yet is rugged and durable. No complicated adjustments are required or possible and yet efficient lubrication is insured. Furthermore, the cups and their collars which serve as caps or covers therefor may be produced by die casting and such is the preferred mode of production.

While I have shown and described several types of construction in which the invention may be embodied, it is to be understood that the con-

structions shown have been selected merely for the sake of illustration or assembly and that various changes in the size, shape and arrangement of the parts may be made without departing from the spirit of the invention or the scope of the subjoined claims.

The invention claimed is:

1. A lubricator comprising a cup having an oil chamber therein, a reservoir receiving opening extending from the top of said cup to said chamber, said cup having a lateral extension formed thereon, spaced vertical openings in said extension, one of said openings extending from the top of the cup through the bottom thereof, another of said openings extending from the top of said cup to said oil chamber, there being a communicating passage between said vertical openings above said chamber, a collar having a portion fitable within said reservoir receiving opening and having a flanged portion engaging and covering the top of said cup and said lateral extension, and an inverted reservoir united to said collar and having a single opening therein, said collar coacting with said cup to position said reservoir so as to control the level of oil in said chamber, said chamber having an outlet below the level of oil therein for connection with oil well type bearings, a capillary wick extending between said vertical openings whereby one of said openings may be connected with sleeve type bearings, the entrance of air to said oil chamber being through such one of said openings.

2. A lubricator comprising a cup having an oil level control chamber, an outlet from said chamber below the level of oil therein for connection with well type bearings, an outlet from said chamber above the level of oil therein, a wick extending from said chamber below oil level to said last named outlet whereby said outlet may be connected to supply oil to sleeve type bearings, a cover for said cup having a collar extending within said chamber to secure said cover in position, and an inverted oil reservoir having a single opening secured within said collar whereby said cover and collar react with said cup to fixedly position said reservoir with its opening so related to said chamber as to maintain a fixed oil level therein.

3. The invention defined in claim 2 and further characterized by an inverted cone of resilient sheet metal having a diameter of a size larger than the opening in the reservoir, said cone being compressed and inserted within said reservoir, through said opening to act as a stopper therefor, a depending stem on said cone extending from said reservoir and of sufficient length to contact the bottom of the oil chamber to raise said cone free from said opening when said reservoir is positioned as set forth in claim 2.

CARL L. DAUN.
